UNITED STATES PATENT OFFICE.

OTTAR T. HAIG, OF JAMAICA PLAIN, MASSACHUSETTS.

VALVE-GRINDING TOOL.

1,391,892.

Specification of Letters Patent. Patented Sept. 27, 1921.

Application filed September 15, 1920. Serial No. 410,520.

To all whom it may concern:

Be it known that I, OTTAR T. HAIG, a citizen of the United States, residing at Jamaica Plain, in the county of Suffolk and State of Massachusetts, have invented an Improvement in Valve-Grinding Tools, of which the following is a specification.

This invention relates to a tool especially adapted for grinding in the puppet valves of internal combustion engines, although well adapted for grinding in valves of other types of engines.

The preferred method of grinding in a puppet valve is to reciprocate the valve on its seat through a few degrees a suitable number of times with a layer of suitable cutting material between the valve and its seat and then advance or partially rotate the valve a few degrees and repeat the reciprocating movement; until the valve has been rotated a complete revolution.

An object of my invention is the provision of a tool adapted to impart to the valve both the reciprocating movement and the rotary movement at will by a reciprocating and rotary movement of its operating handle.

A further object of the invention is to provide a valve grinding tool which may be used on practically all types of automobile engines, will be strong, durable, easily operated to reciprocate and rotate the valve in any position of the operating handle about its valve engaging component and inexpensive to manufacture.

Figure 1 is a side view of a valve grinding tool embodying my invention in engagement with a valve and arranged to reciprocate it by a reciprocating movement of the operating handle.

Fig. 2 is an end view of the valve grinding tool of Fig. 1.

Fig. 3 is a section along lines 3—3 of Fig. 2.

Fig. 4 is a plan view of the operating handle locking collar.

Fig. 5 is a side view of the valve grinding tool arranged to reciprocate the valve by a reciprocating angular movement of the operating handle about its axis.

Fig. 6 is a plan view of the operating handle and its associated components detached from the valve-engaging rod.

Fig. 7 is a plan view of the valve-engaging rod removed from the operating handle.

Fig. 8 is a detail of the valve-engaging

rod having a modified form of valve-engaging blade detachably connected therewith.

Fig. 9 is a plan view of a collar adapted to hold the operating-handle frame in position on the supporting-member.

As here shown, the valve grinding tool embodying my invention includes the valve-engaging rotatable rod or shaft 10 and the operating handle 11 which is angularly disposed with respect to said rod 10 and is adapted to be reciprocated in a vertical plane to angularly reciprocate said rod and which is also adapted to be angularly rotated about its axis to angularly rotate said rod 10.

Said rod 10 has a slot in its lower end in which the valve-engaging blade is detachably secured by the screw 12^a. Some valves have a milled slot in their heads and for these valves the blade 12 having a curved lower face will be employed. Other valves have two holes in their top face and for these valves the tool 13 (Fig. 8) having the prongs 13^a will be employed. For other types of valves a suitable blade will be used.

The rod 10 is of suitable length to extend into the valve cage or recess and to extend sufficiently above the top of the engine to clear obstructions. The upper end of said rod 10 is provided with the handle 14 which is swiveled on said rod by suitable connecting means as the pin 14^a engaging the groove 10^a in the end-portion of said rod. Said rod intermediate its length carries the operating mechanism by which it is reciprocated and rotated to reciprocate and rotate the valve.

Said operating mechanism includes the pinion gear 15 fixed to said rod by the pin 15^a or other suitable means. A supporting-member having the tubular portion 16 is received on said rod above and rests upon the gear 15 and said rod is journaled in said tubular portion. A collar 17 is fixed on said rod above said supporting-member and said collar and said gear 15 serve to restrain said supporting-member on said rod against axial movement thereon. The rod, however, is free to rotate within said supporting member.

Said tubular portion is provided with a cylindrical extension 18 disposed at right angles thereof adapted pivotally to support the operating handle. An idler bevel gear 19 having the hub 20 is rotatably disposed on said extension and is in mesh with the pinion gear 15 on said rod 10. The operating handle is supported by the frame hav-

ing the two arms 21 and 22 disposed at right angles to each other. Said arm 21 has an aperture therethrough in which the hub 20 of the idler gear 19 is received; and said arm 5 is adapted to pivot on said hub. A collar 23 fixed to said extension 18 beyond the hub of said gear and said frame serves to retain the said gear and frame operably in place. The other arm 22 of said frame is provided with 10 a bearing therein in which the operating handle 11 is rotatably disposed. The inner end of said handle extends inwardly beyond said arm and a pinion gear 25 is secured thereon and meshes with the idler gear 19.

15 It will be evident that, with the construction above set forth, a rotary movement of the operating handle about its axis will transmit motion through the idler gear to rotate the shaft 10; and a reciprocatory movement 20 of said shaft will be obtained by a reciprocatory movement of the rod about its axis, in the same manner. If the handle is grasped by the hand sufficiently firmly to restrain it from rotary movement, and the 25 handle is reciprocated about its pivotal connection with said shaft 10, the idler gear 19, and the pinion gear 25 will be locked together and the shaft 10 will be reciprocated. After the shaft, and the valve in engagement 30 therewith, has been sufficiently reciprocated in this manner, the valve may be advanced by partially angularly rotating said handle 11 about its axis.

As an added feature of the invention, I 35 provide locking means by which the operating handle 11 may be restrained from rotary movement as the handle is reciprocated about its pivot to reciprocate the valve. Said means includes the locking-collar 26 which 40 may be removably fixed to said handle 11 adjacent the outer face of said arm 22 by the screw 27. Said collar has a plurality of semi-circular locking recesses 28 therein. Said arm 22 has a recess 29 extending there- 45 in from its outer face in which the compression spring 30 and the ball 31 are received. Said ball is adapted partially to extend into the recesses 28 of the locking collar thereby to hold said collar and consequently the operating handle to the frame 50 against rotation. If a sufficient rotational effort is applied to said handle 11, however, the ball will be depressed in its recess to permit such rotation.

55 In some types of automobile engines, the location of the valves are such that the grinding is best accomplished by the reciprocatory movement of the operating handle about its axis without recourse to the recip- 60 rotatory movement of the handle about its pivot. Conveniently to permit this operation, the locking collar 26 will be loosened and moved along said handle from its position adjacent said frame to some position as 65 shown in Fig. 5 and the locking ball 31 will

be removed from its recess in the arm of the frame. The operating handle 11 may then be rotated and will transmit its movement through its gear 25 and its gears 19 and 15 to the rod 10 as before.

70 It will be noted that with the device as above described, the operating handle may assume any position about the rod or shaft 10; and the valve may be reciprocated and rotated in any such position of the operating handle. This is a highly desirable feature inasmuch as, due to the compact disposition of the engine components and its appurtenances, there is a limited choice of 75 locations of the operating handle when the 80 device is in position to grind the valves.

I claim:

1. A valve grinding tool comprising a rotatable, valve-engaging rod, an operating handle, and means connecting said handle and rod admitting of a reciprocatory movement of said handle in the plane of said rod to reciprocate said rod and a rotary movement of said handle to rotate said rod.

2. A valve grinding tool comprising a rotatable valve-engaging rod, a rotatable operating handle pivoted to reciprocate in the plane of said rod, and connections between said handle and rod by which a reciprocatory movement of said handle about its pivot will reciprocate said rod, and a rotary movement of said handle will rotate said rod.

3. A valve grinding tool comprising a valve-engaging rod, a gear fixed thereon, a handle-supporting member loosely mounted on said rod above said gear, an operating handle pivotally supported by said supporting member to reciprocate in the vertical plane of the tool, and a gear connecting said handle and first named gear by which the reciprocatory movement of said handle will reciprocate said rod.

4. A valve grinding tool comprising an operating-handle supporting-member, a rotatable operating handle pivoted thereto to reciprocate in the vertical plane of the tool, a valve-engaging tool rotatable in said supporting-member, and means including gearing connecting said rod and handle by which a reciprocatory movement of said handle about its pivot will reciprocate said rod and a rotary movement of said handle will rotate said rod.

5. A valve grinding tool comprising an operating-handle supporting-member, an idler gear rotatably supported thereon, a valve-engaging rod rotatable in said supporting-member, a pinion gear fixed to said rod meshing with said idler gear, an operating handle pivotally supported by said supporting-member, and a gear fixed to said handle meshing with said idler gear to rotate it.

6. A valve grinding tool comprising an

- operating-handle supporting-member, an idler gear rotatably supported thereon, a valve-engaging rod rotatable in said supporting-member, a pinion gear fixed to said rod meshing with said idler gear, a rotatable operating-handle pivotally supported by said supporting-member, and a gear fixed to said handle meshing with said idler gear to rotate it also arranged to lock said handle 5 to said idler gear whereby to admit of a reciprocatory movement of said gear and handle as a unit.
7. A valve grinding tool comprising an operating-handle supporting member having a lateral extension, an idler gear rotatably mounted on said extension, a valve-engaging rod rotatable in said member, a gear fixed to said rod meshing with said idler gear, a frame pivotally supported by the lateral extension of said supporting member having an operating-handle bearing, an operating handle rotatably received in said bearing, and a gear fixed to said handle meshing with said idler gear.
- 25 8. A valve grinding tool comprising a valve-engaging rod, an operating-handle, means pivotally angularly supporting and rotatably connecting said handle and rod whereby said handle may be reciprocated about its pivot to reciprocate said rod, and rotated to rotate said rod, and means releasingly to lock said handle against rotary movement.
- 35 9. A valve grinding tool comprising a supporting member, an idler gear rotatably supported thereby, a valve-engaging rod rotatable in said member, a gear fixed on said rod meshing with said idler gear, a frame pivotally mounted on said supporting member, an operating handle rotatably supported in said frame, a gear fixed to said handle

meshing with said idler gear and means releasingly to lock said handle to said frame against rotation.

10. A valve grinding tool comprising a supporting-member, an idler gear rotatably supported thereby, a valve-engaging rod rotatable in said member, a gear fixed on said rod meshing with said idler gear, a frame pivotally mounted on said supporting member, an operating handle rotatably supported in said frame, a gear fixed to said handle meshing with said idler gear and spring-pressed means carried by said frame arranged releasingly to engage said handle 50 to hold it against rotation.

11. A valve grinding tool comprising a valve-engaging rod, a pinion gear fixed thereon, an operating-handle supporting-member loosely received on said rod above 60 said gear, said member having a lateral extension, an idler gear having a hub rotatably mounted on said extension, a frame pivotally mounted on the hub of said idler gear, a collar fixed to said extension beyond 65 said idler gear and frame, a handle journaled in said frame and a gear fixed to said handle meshing with said idler gear.

12. A valve grinding tool comprising a valve-engaging rod, a pivoted and axially 70 rotatable operating handle laterally extended from said rod, and speed-up gearing connecting said rod and handle whereby a rotary movement of said handle results in a rotary movement of said rod and a reciprocatory movement of said handle results in an enlarged reciprocatory movement 75 of said rod.

In testimony whereof I have signed my name to this specification.

OTTAR T. HAIG.
